UNITED STATES PATENT OFFICE.

HENRY F. SAMSON, OF OAKLEY, IDAHO.

WRENCH.

Specification of Letters Patent.

Patented Mar. 8, 1921.

1,371,118.

Application filed October 6, 1919. Serial No. 328,717.

To all whom it may concern:

Be it known that I, HENRY F. SAMSON, a citizen of the United States, residing at Oakley, in the county of Cassia and State 5 of Idaho, have invented certain new and useful Improvements in Wrenches, of which the following is a specification.

My invention has reference to wrenches, clamps, claws, or other gripping, fastening 10 or securing devices consisting of jaws capable of movement toward and relatively to each other, and my invention is particularly intended to provide means whereby the inclination of the jaws, clutches or gripping 15 means which form the operating parts of devices of this kind, may be inclined, so as to make such devices particularly adapted for the taking hold of, grasping or securing of round articles or of such having inclined 20 or irregular surfaces, and it is one of the objects of my invention by adjusting and changing the inclination of the gripping means, jaws or the like toward and relatively to each other, to minimize the liability 25 of slipping of the jaws, and furthermore, to generally increase the usefulness and applicability of devices of the kind referred to. Other objects and advantages will be 30 come apparent as the specification proceeds.

My invention is shown in a preferred 35 form of construction on the accompanying drawing in Figure 1 in elevation as applied to a wrench, similar to a so-called monkey-wrench. Fig. 2 is a longitudinal section of the movable part of the wrench. Fig. 3 shows the relatively stationary part in elevation and part section. Fig. 4 is an edge view of Fig. 3. Fig. 5 is a view of a modified construction.

In the drawing:—1 is the shaft of the 40 wrench at one end of which is provided the angularly, preferably vertically disposed jaws 3, having the usual serrated edge 4. The shaft 1 may serve as a guide for the 45 movement of the relatively movable jaw 5, having the serrated edge 6 opposite the edge 4, and being provided with a longitudinally 50 extending square shaped guideway 8. The dimensions of this guideway are somewhat larger than the dimensions of the shaft, and at its inside it is provided with a cam sur-

face 10 the distance of whose highest point from the opposite side of the guideway 8 is equal or substantially so to the width of the shaft 1. In the preferred form of construction the cam surface is provided with inclined surfaces 11, 12 against which the shaft 1 is adapted to rest. 9 is a screw threaded hole opposite the cam surface or opposite one of the inclined surfaces and 60 adapted for the reception of a screw 7 the inner end of which is adapted to enter an inclined recess or slot 2 in the shaft 1. After the movable jaw 5 has been adjusted in its relatively angular position by turning 65 or pivoting it on the highest point of the cam surface 10, it is locked in position by tightening the screw 7 in the inclined key way or recess 2 of the shaft; the relatively 70 stationary jaw 3 is also provided with an inclined abutting surface 13 for contact with the confronting surface of the relatively movable jaw 5.

It is obvious that my invention is susceptible of various changes and modifications 75 in accordance with local conditions or to adapt itself to different kinds of material, and to suit the convenience of the user, and without departing from the spirit of my invention as expressed in the claim hereunto 80 appended. Thus for instance, I may change the location and inclination of the abutment 85 13 or the position and inclination of the surfaces 10, 11, and the relative arrangement of the securing screw with corresponding recess or keyway, and various other changes may be introduced.

The terms movable and immovable jaws 90 are only relative, as I may hold the jaw 5 stationary, and displace the jaw 4 or I may move both jaws relatively to each other.

What I claim is:—

In a gripping device in combination two 95 relatively movable jaws, guiding means for said jaws allowing longitudinal and relatively transverse movement of the jaws, there being inclines on said guiding means, locking means in one jaw, and there being inclined recess in the other jaw engageable with said locking means.

In testimony whereof I affix my signature.

HENRY F. SAMSON.
